CLAIM

The ornamental design for a skater's learning aid, as shown and described.

DESCRIPTION

FIG. 1 is a top plan view of a skater's learning aide showing my new design;

FIG. 2 is a side elevational view thereof;

FIG. 3 is a front elevational view thereof;

FIG. 4 is a rear elevational view thereof; and,

FIG. 5 is a bottom perspective view of blade support member shown on an enlarged scale partially in fragment.
